CLAIM

The ornamental design for a jewelry link, as shown and described.

DESCRIPTION

FIG. 1 is a perspective view of a jewelry link showing my new design;

FIG. 2 is a top plan view;

FIG. 3 is a side elevational view;

FIG. 4 is a bottom plan view;

FIG. 5 is a top elevational view;

FIG. 6 is a bottom elevational view;

FIG. 7 is a perspective view of a jewelry link shown in a position of use, the broken line showing of a hand and adjoining links is for illustrative purposes only and forms no part of the claimed design;

FIG. 8 is a perspective view of a jewelry link showing a second embodiment of my new design;

FIG. 9 is a top plan view of FIG. 8;

FIG. 10 is a side elevational view of FIG. 8;

FIG. 11 is a bottom plan view of FIG. 8;

FIG. 12 is a top elevational view of FIG. 8;

FIG. 13 is a bottom elevational view of FIG. 8; and,

FIG. 14 is a perspective view of FIG. 8 shown in a position of use, the broken line showing of a hand and adjoining links is for illustrative purposes only and forms no part of the claimed design.
